TRAFFIC CONTROL SIGNAL

Charles B. Watson, Omaha, Nebr., assignor of
fifty-one per cent to Fay G. Johnson, Omaha,
Nebr.

Application April 3, 1936, Serial No. 72,542

3 Claims. (Cl. 177—327)

Heretofore, to my knowledge, attempts to produce traffic signals with neon and other luminous tubes have been unsuccessful by reason of the fact that the present art affords tubes not to exceed 15 millimeters in effective diameter and their position in the structure has been such that, when exposed to sunlight, illumination produced is negligible. Another difficulty encountered by the present art is the fading of color in such tubes 5 in cold weather at which time the green color is particularly susceptible and will turn white during cold weather. It has also been found difficult to operate gaseous discharge tubes due to certain difficulties in handling the high voltages necessary for the tubes, particularly in the flasher.

It is therefore the object of my invention to provide a traffic control signal wherein the luminous gaseous discharge elements are of relatively large diameter and great light intensity.

Another object of my invention is to provide such a signal wherein the luminous elements are suitably shaded from extraneous light to increase their visibility and color.

Another object is to provide for suitable self-heating of the tubes to keep same warm in cold weather to increase their efficiency in such weather and to maintain their color.

A further object of my invention is to provide a positive continuous, visual informative traffic control signal to minimize intersection hazards, and having a threefold, instantaneous and simultaneous, visual indication showing the existing direction of traffic, the time that has elapsed since the commencement of a particular signal, and the time that must elapse before a change of traffic direction will occur.

A further object is to provide a signal having a minimum number of illuminable signal elements or tubes, each element being adapted to be seen from opposing sides for signally controlling traffic from those sides.

A further object is to provide illuminable signal elements having a high luminosity with low current consumption.

A further object is to provide signal means for aiding in clearing an intersection at the time of signal change.

A still further object is to provide means for adequately controlling the electric current supplied to the signal elements or indicators.

Other objects are to provide an illuminant having a high atmospheric penetration characteristic in order that signals may be seen from relatively great distances; to provide a signal having a uniformly moving time indication for the psy-

chological effect of concentrating the attention upon the cycle of operation; to provide a signal with the above characteristics having a weather-proof head enclosing the illuminable elements; and to provide a signal with low operating costs. 5

The foregoing and other aims and objects will be apparent from the detailed description hereinafter appearing when taken in connection with the accompanying drawings wherein:

Figure 1 is an elevational view of my traffic control signal.

Figure 2 is an enlarged elevation of the signal head of my invention with the corner glass panels removed to provide an unimpaired view of the tubes and their vertical, superposed sections. 15

Figure 3 is a plan view of the signal head.

Figure 4 is a horizontal section through the signal head taken on line 4—4 of Figure 2.

Figure 5 is a plan view of a metal plate on the floor of the base of the signal head having notches 20 for accepting the ends of the glass panels and openings for receiving the tube supports.

Figure 6 is an enlarged detailed partial section showing the seal between the vertical edges of the glass panels and the vertical edges of the side 25 shields.

Figure 7 is a wiring diagram of a signal head having four illuminable elements, each comprising a plurality of longitudinally extending, spirally coiled, tube sections in superposed relation. 30

Figure 8 is a diagrammatic view of cam operated contact switches of the flasher or distributor.

Referring more particularly to the drawings, which illustrate the preferred embodiment of the invention, reference numeral 20 indicates a 35 standard upon which is supported a signal head, said head comprising a base 21 substantially square in cross-section for a signal head with four faces or sides for controlling traffic from four directions. A shade cap 22, to shade the 40 illuminable elements or signal tubes from the top, is supported in spaced relation above the base 21 by vertical tube shields 23, each side or face of the head being provided with a shield 45 extending centrally upward between base 21 and cap 22. The shields 23 are secured at the bottom to base 21 by screws 24 and at the top to the shade cap 22 by bolts 25 in the upper ends thereof, said upper ends being inturned over the cap and terminate in pointed portions that angularly 50 meet centrally on the cap.

The control of traffic is effected by illuminable signal elements or indicators R1, G1, R2 and G2, preferably arranged vertically in the head. Each illuminable signal indicator gives off, when illu- 55

minated, a single, positive color, as red in the tubes numbered R1 and R2, and green in the tubes indicated by reference numerals G1 and G2. Each illuminable indicator is composed of a plurality of spirally coiled tube sections arranged in superposed relation to give the general appearance of a single, continuous spirally coiled illuminable tube. The tubes are spirally coiled to increase the effective width of the signal and to provide lights of extreme brilliancy with a maximum concentration of lumens from an illuminated signal of a given width and length.

In neon tubes the diameter of a tube largely determines its brilliancy when illuminated. A small diameter tube is much more brilliant than a large diameter tube when the electric current provided is substantially the same. With a small diameter tube, low current apparatus may be used but with a large diameter tube it is necessary to use high current apparatus to get illumination therefrom that even approximates a small diameter tube in brilliancy. With the use of high current apparatus costs and operative difficulties increase. By the use of coiled, small diameter tubes a brilliantly illuminated signal tube may be provided in the signal with the use of low current apparatus and the coiling of the tube greatly increases the effective illuminable width of the signal indicator, thus securing the effect of a very large diameter tube with the use of low current apparatus. Signal tubes of substantially any desirable coiled diameter may be used in the signal head.

Each illuminable indicator is in sections and said sections are supported in vertical alignment on rods 26 received centrally in said sections which are coiled. The lower ends of the rods 26

are received in holes 27a in a plate 27 on the floor of the base 21. Each indicator extends vertically in the head and substantially parallel with its respective shield 23, the shield being in front of its respective indicator, relative to the respective side or face of the head, to shade said indicator from view from the direction of said face or side as well as to shade it from extraneous light such as sunlight. Neon tubes, as before stated, will suffer as to brilliancy in sunlight but by shading the tubes their brilliancy is substantially unimpaired or undiminished when placed on the street.

The respective tube sections of each illuminable indicator are provided with end electrodes, which electrodes in an assembled indicator are numbered respectively 1, 2, 3, 4, 5, 6, 7, 8, 9, 10, 11 and 12, and each tube section is provided with an intermediate electrode I. The electrodes are received between outwardly extending, vertically parallel flanges 28a of a vertical contact board 28, said board being in the form of an X in horizontal cross-section and having said flanges extending outwardly from the ends of said X shaped board, both the board and the flanges being of suitable insulating material and formed integrally with each other.

Spring contacts 29 are provided between the flanges 28a in suitable spaced relation for contact with the respective electrodes of the illuminable indicators. The flanges of the board are adapted to conceal the respective electrodes; and said flanges and board also conceal the respective indicators from view from the side opposite their respective vertical shields 23. Each indicator is therefore shielded from view from the front and rear, relative to its respective side; and relative to such side each indicator is visible from two directions, viz., laterally of said face, the visible

sides of said elements being at substantially right angles to the concealed sides.

The illuminable elements or signal indicators are arranged in the head with a red indication and a green indication, R1 and G2 on opposite sides of the electrode contact board for signalably controlling traffic flowing in opposite directions as east and west or north and south. The elements R2 and G1 are arranged in their respective sides of the head for controlling traffic flowing at substantial right angles to that controlled by the indicators R1 and G2. The indicators are operated in sets or pairs, one red and one green, R1 and G1 respectively, being operated together in unison with each other, each of said tubes being visible at substantially right angles to each other. Therefore traffic flowing in east and west directions may be signalled to proceed by the element G1 and the north and south traffic simultaneously signalled to stop by the element R1. The illuminable elements R1 and G1 operate simultaneously together and the indicators R2 and G2 operate simultaneously together, but the respective sets of tubes are operated alternately.

As above stated the signal indicators are arranged in the head with R1 and G2 on opposite sides of the head and as to each other said elements are illuminated alternately thereby signalably controlling traffic flowing in opposite directions, viz., north and south to alternately signal said traffic to stop and to proceed. The indicators R2 and G1 operate similarly to alternately signal east and west traffic to stop and proceed and the alternations of lighting of the indicators are such that when north and south traffic is signalled to stop, the east and west traffic is signalled to proceed, and vice versa. More specifically, traffic flowing north and south is signaled to stop by the indicator R1 and the east and west traffic is signalled to proceed by the indicator G1 as said indicators are operated together and the reverse is true when the indicators R2 and G2 are illuminated alternately with the indicators R1 and G1.

As an aid to clearing the intersection the head is provided with two signals, each comprising a neon tube forming the word Stop, said signals being mounted on the head on adjacent sides facing approaching traffic. Said stop signals are illuminated at such time that approaching traffic will see its respective stop sign illuminated during the period of illumination of the last section of the green proceed indicator and said stop sign will remain illuminated with its respective stop indicator during the entire cycle of said stop indicator. The sign will be extinguished during the major portion of the cycle of the respective proceed indicator.

By illuminating the stop signal while the last section of the respective proceed indicator is illuminated, traffic is signalled to "stop" before the change of direction of traffic flow is signalled, thereby giving traffic and pedestrians an opportunity to get off the intersection before such change of direction of traffic flow is made.

The wiring arrangement of the signal is shown in detail in Figure 7. The source of electricity to energize the indicators is a commercial circuit 30 and 31 carrying a commercial load of 120 volts. Wire 31 leads into a flasher F having two series of contacts FR1—FG1 and FR2—FG2 respectively, said wire 31 being connected to the inner bank of contacts, from 1 to 11 inclusive, in each series.

A description of the operation of series 75

FR1—FG1 only will be made inasmuch as the operation of the series FR2—FG2 is a duplication thereof, but it should be understood that the respective series are operated alternately.

5 Wire 30 of the commercial circuit is connected to the inner contacts 12, 13 and 14 of each series, contact 12 being the change over control for the respective indicator set circuits. The circuits controlled by contacts 13 and 14 are 10 for the signs forming the word Stop and will be described below.

Wires of one side of the secondaries of the transformers are connected to the respective electrodes of the tubes of the R1 indicator numbered 1 to 12 inclusive, said secondary wires being also numbered 1 to 12 inclusive to correspond with the numbers of the electrodes. The wires of the other side of the respective secondaries are connected to the respective electrodes of the 20 tubes of the G1 indicator numbered 1 to 12 inclusive, said secondary wires on this side also being similarly numbered. The intermediate electrodes 1 of corresponding tube sections of the respective indicators are connected by wires 25 32 so that corresponding portions of each indicator are supplied with current by the same transformer.

The flasher F controls the primary circuits of the transformers and beginning the cycle of 30 operation for the set of indicators R1—G1, cams 33 operate, through rollers 34, to move the entire inner bank of contacts 1 to 12 inclusive into contact with the corresponding contacts of the outer bank, thereby supplying the primaries of 35 all the transformers for the R1—G1 set of indicators with current. The transformers step up the voltage to supply the tubes with suitable current to illuminate same and when the flasher closes the circuits to all the transformers for a 40 set of indicators the indicators of such set are illuminated their entire length.

An electric motor, not shown, operates the flasher and causes rotation of the shaft 35 and cams 33 secured thereon. As the cams rotate 45 the contact is broken between contacts 1 thereby cutting out the lower transformer or transformer 1, which has its secondary connected to the top portion of the upper tube section, and extinguishing the upper portion of said upper tube 50 section in both the R1 and G1 indicators.

The second transformer still supplies current to the lower half of the sections of the respective indicator tubes, the secondary of said transformer being connected to electrodes 2 thereof 55 and the circuit is completed between the intermediate electrodes of the upper tube sections through wire 32 thereof.

Further rotation of the cams cuts out the second transformer so that another portion of the 60 indicators is extinguished and such operation of the flasher continues until all the sections of the indicators of the set are extinguished. The operation of the respective tube sections of the set is the same for each section as for the top section 65 above described.

After the entire cycle is completed for a set of indicators, and said set is entirely extinguished, the other set, or, in this case, R2—G2 is fully 70 illuminated and then progressively extinguished in decrements from the top downwardly until the entire length of the indicators of the set is extinguished, whereupon the first set of indicators is again illuminated and goes through its cycle.

75 It should be noted that by having the flasher

control the circuits of the transformer primaries said flasher need only handle 120 volts, which voltage is comparatively low and easy to handle. Thus it is unnecessary for the flasher to handle the relatively high voltages of the secondaries 5 which high voltages would be very difficult to control without causing arcing in said flasher.

The circuits for the tubes forming the word Stop are controlled by contacts 13 and 14 of the flasher F. The stop signal for the R1 indicator 10 and the G2 indicator is illuminated, by operation of the respective cam closing the circuit of the contacts 13 and supplying current to the primary of transformer 36 on the R1—G1 side of the flasher, during the entire cycle of illumination of the indicator R1. It should be kept in mind that indicators R1 and G2 are seen from the same directions, and that indicator G1 is seen from a direction at substantial right angles to the direction from which indicator R1 is seen. 15 The stop signal that is illuminated while the R1 indicator is going through its cycle is seen from the same direction as indicator R1 relative to approaching traffic on the side of the street adjacent to the signal. 20

This stop signal is extinguished during the major portion of the cycle of illumination of the G2 indicator, said stop signal being illuminated only during the period of individual illumination of the last section of the said indicator. The circuit to said stop signal is completed by the closing of contacts 14 on the R2—G2 of the flasher, to the primary of said transformer, during the time specified above. 30

The operation of the stop signal for the R2 35 and G1 indicators is similar to the operation of the stop signal above described.

The signal head is sealed against the weather by providing glass panels 37 in the interstices between the shields 23. The panel ends are received in notches 38 cut in the corners of the plate 27 and the abutting vertical edges 39 of said panels are sealed by transparent glue or adhesive. The free vertical edges of the panels are provided with channels 40 of rubber received 45 over said edges, a portion of said rubber channels being in intimate contact with the adjacent edges 41 of the vertical shields to form a seal therebetween. The glass panels provide a clear view of the tubes from the unshielded sides and 50 also aid in deflecting away from the tubes extraneous light that may strike same. The panels are set in the head in relation to the respective indicators so that any slight reflection that may occur from the glow of the indicators will not 55 interfere with any other indicator, the angles of said panels being such as to avoid interference and confusion of one illuminated indicator and any other illuminated indicator in the head.

The vertical coiling of the tubes provides ready 60 circulation of air upwardly about the coils. As the lower portion of the tubes is the last to be extinguished during its respective cycle of operation the air at the bottom thereof is heated and rises thereby warming the upper coils. This is 65 a definite advantage especially during cold weather as a warm tube is much more efficient than a cold one and the circulation of warm air about the coils tends to keep the tubes warm throughout their entire length. It will be apparent that to secure the warming of the tubes 70 in this manner said tubes must be in a vertical position.

As the head is sealed against the weather the warm air will also circulate about the tubes 75

and throughout the head and will maintain a sufficiently high temperature in the head to assure the tubes retaining their proper colors when illuminated. Fading of the colors is therefore prevented and the tubes kept in efficient operative condition.

The coiled tubes possess a certain amount of flexibility, the longer the tube the greater its flexibility, and for this reason they will not break easily. Should a tube section go out of order for any reason, it may be removed by removal of the vertical shield 23 in front of the tube. The shield is removed by unscrewing the screw 24 and bolt 25. The rod 26 of the indicator is lifted out of its hole 27a in plate 27 and the indicator removed. The section of the indicator that is out of order is replaced and the indicator returned to its position in the head, after which the shield is replaced.

20 It is to be understood that the indicators may be provided in any desired lengths, having as many sections as may be required for such lengths, and the effective diameter of the indicators may be of any suitable size.

25 Although I have herein shown and described my preferred embodiment of the invention, it is to be understood that various changes and modifications may be made therein within the scope of the appended claims without departing from 30 the spirit and scope of my invention.

Having thus described my invention what I claim is:

1. In a traffic control signal, the combination, a head, a plurality of electrically illuminable signal indicators for signaling stop and proceed, shielding means for shielding said indicators from sight from directions at substantial right angles to the direction of traffic flow controlled by said indicators, the stop indicator signaling traffic flowing at substantial right angles to that signaled by the proceed indicator, each indicator comprising a plurality of spirally coiled gaseous discharge tube sections arranged in superposed relation, each indicator section being provided 35 with an electrode adjacent each end and an intermediate electrode, the respective intermediate electrodes of the respective indicators being electrically connected together, a transformer for 40 each portion of each tube section, said transformers supplying current to the respective tube portions from their secondary coils, one side of the secondary for a tube portion being connected to an end electrode of a tube section of an indicator and the other side being connected to the corresponding end electrode of the other indicator, and means for supplying electric current 45 to the transformer primaries in such a manner that the indicators will be first fully illuminated and then progressively darkened a portion of a 50 section at a time from one end until the entire length of the indicators will be extinguished, said indicators being operated simultaneously.

2. In a traffic control signal, the combination, a head having four sides, a vertical electrode contact board mounted centrally in the head, a vertical shield for each side of the base secured

centrally thereof, shading means secured to the upper ends of the shields, a vertical electrically illuminable indicator between each shield and the electrode contact board in substantially parallel alignment therewith, opposite indicators being 5 of different colors when illuminated to respectively signal stop and proceed, each indicator comprising a plurality of spirally coiled gaseous discharge tube sections arranged in superposed relation to provide the appearance of a continuous indicator, each indicator section being provided with an electrode adjacent each end and an intermediate electrode, said electrodes being in operative association with the electrode contact board, the intermediate electrodes of diagonally disposed stop and proceed indicators being 10 electrically connected together, a transformer for each portion of each tube section for supplying current thereto from the secondary coils thereof through the electrode contact board, each tube 15 section having two transformers, one side of one transformer secondary being connected to the upper electrode of one stop indicator and the other side thereof being connected to the upper electrode of the proceed indicator having its intermediate electrode connected with the intermediate electrode of said stop indicator so that 20 said indicators will operate as a set, the other transformer is similarly connected to the lower electrodes of the tube section, and means for 25 supplying electric current to the primaries of the transformers in such manner as to first illuminate one set of indicators throughout their entire length and then to progressively extinguish 30 same from one end a portion of a tube section 35 at a time until the set is entirely extinguished and then to alternately illuminate the other set of indicators and progressively extinguish same from one end a portion of a tube section at a 40 time until said set is entirely extinguished.

3. In a traffic control signal, the combination, a set of electrically illuminable gaseous discharge indicators, each indicator comprising a plurality of spirally coiled gaseous discharge tube sections arranged in superposed relations, each indicator 45 section being provided with an electrode adjacent each end and an intermediate electrode, the respective intermediate electrodes of the respective indicators being electrically connected together, a transformer for each portion of each tube section, said transformers supplying current to the respective tube portions from their secondary coils, one side of the secondary for each tube portion being connected to an end electrode of a tube section of an indicator and the other side 50 being connected to the corresponding end electrode of the other indicator, and means for supplying electric current to the transformer primaries in such manner that the indicators will be first fully illuminated and then progressively 55 darkened, a portion of a section at a time, from one end until the entire length of the indicators will be extinguished, said indicators being operated simultaneously.

CHARLES B. WATSON.
